ATTORNEY

UNITED STATES PATENT OFFICE.

CHARLES B. HOTCHKISS, OF BROOKLYN, NEW YORK.

RADIATOR.

SPECIFICATION forming part of Letters Patent No. 237,869, dated February 15, 1881.

Application filed December 27, 1879.

To all whom it may concern:

Be it known that I, CHARLES B. HOTCHKISS, of the city of Brooklyn, in the county of Kings and State of New York, have invented 5 certain new and useful Improvements in Radiators, of which the following is a specification.

In the accompanying drawings, Figure 1 represents a vertical central section of my improved radiator, and Figs. 2 and 3 are horizontal sections of the same, respectively on line *x x* and *y y*, Fig. 1.

Similar letters of reference indicate corresponding parts.

This invention has reference to an improved radiator for gas or petroleum heating-stoves, by which the air is heated in a high degree and discharged at the base of the radiator, the same being also arranged with illuminating-windows.

The invention consists of a sheet-metal radiator having interior flues, which are open at the top and closed at the bottom, but arranged to connect with openings near the base of the radiator, so that the air heated by the flame of the burner is first carried up and then drawn down in the flues to be discharged through the openings, the lower parts of the flues being provided with inclined mica bottoms for producing the effect of illumination.

Referring to the drawings, A represents a gas or petroleum burner of any approved construction, and B a radiator, which is preferably made of sheet metal and closed tightly at the top by a cover, C. At the inside of the radiator B are arranged a series of flues, D, which are open at the top and closed at the bottom, said flues extending from a point near the base of the radiator, but on a level with or above the burner or other source of heat, to a point near the top of the same. The heated air from the burner passes first to the top of the radiator, and heats thoroughly the surface not taken up by the flues, and also the inner walls of the flues, so as to create a downward

draft in the same, owing to the partial vacuum formed in the lower parts of the flues by the greater heat exerted thereon by the flame. The heated air is thereby drawn from the top of the radiator down into the flues and emitted through discharge-openings *b* of the radiator, as indicated by arrows in Fig. 1.

For the purpose of also obtaining the pleasing effect of illumination in the radiator, the flues are arranged at the lower ends with inclined or slanting mica bottoms *d*, which are supported in guideways of the side walls of the flues, so as to be conveniently removed for cleaning or repairs. These inclined mica bottoms are placed back of and in line with the discharge-openings *b*, so that they form windows through which the flame of the burner is seen. In this manner not only a very simple and effective heating apparatus is obtained, but also, by the illuminated windows, a neat and pleasing appearance imparted to the same.

Having thus described my invention, I claim as new and desire to secure by Letters Patent—

1. A radiator for gas and petroleum heating-stoves, provided with interior flues, which are open at the top, and with sliding and removable bottoms back of and in line with the discharge-openings of the radiator, substantially as described.

2. A radiator for gas or petroleum heating-stoves, provided with interior flues, which are open at the top, and closed by inclined bottoms of mica back of and in line with the discharge-openings of the radiator, substantially as and for the purpose set forth.

In testimony that I claim the foregoing as my invention I have signed my name, in presence of two witnesses, this 24th day of December, 1879.

CHARLES B. HOTCHKISS.

Witnesses:

PAUL GOEPEL,
CARL KARP.
